UNITED STATES PATENT OFFICE.

WILLIAM C. STEWART, OF SWAMPSCOTT, MASSACHUSETTS, ASSIGNOR TO UNITED SHOE MACHINERY CORPORATION, OF PATERSON, NEW JERSEY, A CORPORATION OF NEW JERSEY.

CUTTING MACHINE.

Application filed December 30, 1924. Serial No. 758,910.

This invention relates to cutting machines and is herein illustrated as embodied in a machine for skiving the shanks of soles.

In the manufacture of the better grades of boots and shoes, the sole is "shanked-out" by being skived along the opposite margins at the shank portion thereof. The skived portions should be confined to that portion of the sole which lies between the ball line and the heel breast line, since otherwise the thin edge produced by the skiving operation will extend into the forepart of the sole or into the heel seat and mar the appearance of the finished shoe. Ordinarily there are formed at the shank of a sole, in the shanking-out operation, two scarfs one on each margin of the sole, said scarfs being separated by a narrow uncut locality of the same thickness as the original thickness of the sole; but in some cases the shanking-out cut extends entirely across the shank portion so that in effect a single scarf having oppositely inclined beveled portions results. In order, therefore, to promote brevity as well as to avoid certain confusion which might otherwise occur in setting forth the present invention, the scarf or scarfs which result when the sole has been completely shanked-out will be referred to as a single scarf.

This scarf should extend accurately from the ball line to the breast line of any given sole, and since the distance between these two lines varies with soles of different lengths as well as with soles of different styles, provision should be made for producing scarfs of predetermined varying lengths.

The general object of the present invention is to provide an improved machine for carrying out these and similar operations in a rapid and satisfactory manner.

According to one feature of the invention, means are provided for making two separate scarfs on the margin of a blank which overlap lengthwise so as to produce a composite finished scarf which is longer than either of the separate scarfs by which it was produced, in combination with means for varying the extent of the overlap of the separate scarfs so as to vary the length of the finished scarf. By providing means for locating the scarfs properly with respect to the sole, the composite finished scarf may be caused to extend from the ball line to the breast line.

According to another feature of the in-

vention, two cutting mechanisms adapted each to make a cut in a blank are provided, together with means for causing the blank to be operated upon by said mechanisms in succession in such manner that the cuts overlap to produce a finished cut longer than either of the separate cuts.

In the illustrative machine, two skiving mechanisms, each including a matrix roll, are arranged in series, one mechanism being adapted to make the forepart of the scarf at the shank of a sole and the other to make the rear part; and each skiving mechanism has associated with it a feed mechanism which is adjustable to vary the locality in the sole which is presented to the matrix. By thus varying the presentation of the sole, the two scarfs may be caused to overlap more or less and thereby to produce a finished scarf which is shorter or longer as may be desired.

These and other features of the invention, including certain details of construction and combinations of parts, will be described as embodied in an illustrative machine and pointed out in the appended claims.

Referring now to the accompanying drawings,

Figure 1 is a plan of a machine in which the present invention is embodied;

Figure 2 is a central longitudinal section with certain parts shown in elevation; and

Figures 3 and 4 are plans of two soles of the same style but of different sizes with a diagrammatic indication of the manner in which the two overlapping scarfs produce the finished scarf in each case.

The illustrative machine comprises two skiving mechanisms arranged in series. The first mechanism consists of a matrix roll 5, a presser roll 7 and a stationary knife 9. Substantially one-half of the periphery of the matrix roll is cut away to produce a depression 10 the surface of which lies below the surface of all of the remaining portion of the roll except for a narrow zone 11 the surface of which is a continuation of the surface of the cut-away portion 10. The extreme ends of the roll are not cut away at all, since these ends do not come into contact with the blank and are therefore ineffective. Certain portions 13 and 14 of the periphery of the roll, lying one on one side and one on the other of the narrow zone 11, are cut away, but not as deeply as the portion 10,

to form a matrix which is adapted, in co-operation with the presser roll 7 and knife 9, to make the beveled scarf on opposite margins of the soles the path of which is indicated in Figs. 3 and 4 as lying between the lines *a* and *b*. The second skiving mechanism is practically the same as the first except for the shape of its matrix; and to the parts of this second mechanism have been applied the same numerals increased by one hundred as have been applied to those of the first mechanism. This second skiving mechanism is adapted to make the scarf the path of which is indicated in Figs. 3 and 4 as lying between the lines *c* and *d*. It will be noted that these scarfs, *a* to *b*, and *c* to *d*, overlap and result in a finished composite scarf, *a* to *d*, which is longer than either of the component scarfs. It will also be noted that, by varying the extent of the overlap, the extent of the finished scarf may be varied.

Considering the two component scarfs *a* to *b* and *c* to *d*, there is perhaps a slight inaccuracy in the statements which have been made above. The knife 9 actually cuts all the way from *a* to *b* but the knife 109 does not actually cut, or at most cuts a very thin shaving, until it reaches the locality *b*, since the matrix 113, 114 is, throughout most of its extent, of substantially the same depth as that of the matrix 13, 14.

Referring now once more to Figures 1 and 2, and to the first skiving mechanism, the cut-away portion or recess 10 is of sufficient depth to permit that portion of a sole which is engaged by it to pass over the knife 9 without being cut at all. The cutting begins only when the matrix 13, 14 comes into contact with the sole and continues only during such contact. Assuming that the matrix roll 5 and presser roll 7 are turning so slowly that an operator may present the toe end of the sole to the rolls in such manner that, as the sole is drawn between the rolls, the forepart of the sole will pass uncut between the rolls until the ball line *a* is reached, and thereupon the leading end of the matrix will engage the sole and start the cut, it will be evident that the scarf *a* to *b* will be produced. Assuming now that the rolls 105, 107 are also turning slowly, the operator may repeat the procedure with this difference that the matrix 113, 114 is caused to engage the sole at the locality *C*, whereupon the finished scarf, which was started by cutting from *a* to *b*, will be finished by the cut from *c* to *d*.

The present machine contains mechanism for feeding soles to the skiving mechanisms in succession after the manner described above but much more rapidly, said mechanism being adjustable to cause the scarfs *a* to *b* and *c* to *d* to overlap to different extents so as to take care of soles of different

lengths. This feed mechanism comprises two feed slides 15, 17 slidably mounted in the frame of the machine and adjustable simultaneously in the same direction by turning a rod 19 the left-hand end of which is threaded through a lug 20 depending from the feed slide 15 and the right-hand end of which is threaded through a sleeve 21 which in turn is threaded through the split hub of a lug 23 depending from the feed slide 17 and is held in adjusted position by a pinch-screw 25. The extreme right-hand end of the rod has a loose collar 27 which is pivoted at 29 to one end of a link 31 the other end of which is pivoted at 33 to the upper end of a lever 35, said lever being pivoted at 37 to the frame of the machine and having at its lower end a roll 39 which runs in a cam track 41 formed in a cam 43 fast to a shaft 45. When the machine is at rest, it will thus be clear that the rod 19 is held from longitudinal movement so that rotation of it will adjust the feed slides 15 and 17 toward or from their respective skiving mechanisms. The feed slide 15 has an upstanding feed member in the form of a lug 47 and the feed slide 17 an upstanding lug 49 which are adapted to engage the rear edges of the soles in succession and to push the soles forward until the forward ends of said soles are engaged by the rolls of the skiving mechanisms. The soles are placed one at a time upon the feed slide 15 in front of the feed member 47 either by the operator or by suitable automatic mechanism, such for example as by delivering the lowermost sole from a stack in a magazine. The slide, on its forward movement, delivers the toe end of the sole between the depressed portion 10 of the matrix roll 5 and the presser roll 7. The forepart of the sole is carried between the rolls and over the knife without being cut until the matrix 13, 14 comes into engagement with the sole, the locality at which this engagement occurs depending upon the location of the path of reciprocation of the feed lug 47. If, for example, the feed lug 47 has been moved into its extreme right-hand position by turning the rod 19, the cut of the knife 9 will begin at the greatest distance possible from the forward edge of the sole. If, on the other hand, the feed lug 47 has been adjusted into its extreme left-hand initial position, then the cut of the knife will begin at the least possible distance from the forward edge of the sole. Thus by varying the position of the feed lug 47, the location of the path of its reciprocation may be varied and the cut *a* to *b* placed, within limits, wherever desired on the sole. After the cut *a* to *b* has been made, the sole is delivered by a pair of small rolls 51, 53 in front of the feed lug 49 whereupon the sole is presented to the rolls 105, 107 and the scarf from *c* to *d* made.

It has been explained above that the feed lugs 47, 49 are adjusted simultaneously by turning the rod 19; and, where, as in the present case, the machine is adapted to skive the shanks of soles, the adjustment of the feed lugs should be in the same direction but not of the same extent. Let it be assumed, for example that the feed lugs 47, 49 are in positions to present comparatively short soles, such as that shown in Fig. 3, in such manner that the separate scarfs will have the locations on the sole shown in that figure and that the composite, completed scarf will extend, as shown, from the ball line *a* to the breast line *d*, and that it is now desired to skive the shank of the longer sole shown in Fig. 4. Because the distance from ball line to rear edge is greater on a larger sole, feed lug 47 must be adjusted rearwardly (to the left) in order to have the first cut start at the ball line of the larger sole. Because the distance from breast line to rear edge is greater on a larger sole, feed lug 49 must be adjusted rearwardly in order to have the second cut end at the breast line of the larger sole. If, however, both feed lugs were adjusted rearwardly the same distance, both cuts would be moved back, so to speak, the same distance. The completed cut (made up of the two) would then be of the same length as the larger sole as it was on the smaller one. Consequently, in order to decrease the extent of overlap of the two scarfs *a* to *b* and *c* to *d* so as to make the completed scarf on the larger sole extend from the ball line to the breast line, the feed lug 49 should be adjusted rearwardly but to a less extent than is the feed lug 47. To this end the threads 55 and 57, at the opposite ends of the rod 19, are both right-hand threads; but the threads 55 are coarser than the threads 57, the pitches of these threads being so chosen that soles of different lengths may be properly skived.

In skiving the shanks of soles in the manner which has been described above, it is desirable that the soles be held from angular movement so as to be presented in succession to the skiving mechanisms in such manner that a selected axis of the sole (the lengthwise axis in the present case) shall be maintained in the same relation to the edges of the knives of both mechanisms. To this end, each of the feed slides 15, 17 is provided with means for centering the sole laterally, said means comprising a pair of breast-line guides and a pair of ball-line guides. Referring first to the feed slide 15, there are pivoted to the rear portion thereof at 63 and 64, two arms 65, 67, the rear ends of which are geared together at 69 and the forward ends of which have upwardly turned ends 66, 68 adapted to engage opposite points on the edge of the sole in the vicinity of the breast line thereof. A screw 71, threaded

through a lug on the frame of the machine, is located in position to engage the rear end of the arm 64 and open the arms at their forward ends when the feed slide is at the limit of its rearward movement. Also carried by the slide 15 are two sets of parallel arms 73, 75 pivoted at their rear ends to lugs formed on the feed slide and having pivoted to their forward ends ball-line guides 77, 79. The flat, operative faces of these guides engage opposite edges of the sole in the vicinity of the ball line of the sole. The inner arm 73 is connected with the inner arm 75 by a link 81 in such manner that the guides 77, 79 are compelled to move in unison toward and from each other.

In order to open the two sets of guides when the feed slide has been moved to its rearward position so as to permit a sole to be placed upon the slide, as well as to close the sets of guides upon the sole when the feed slide moves forward, the arm 67 has integral with it an arm 83 which is connected with a part of the feed slide by a tension spring 85 so that, after the arms 65, 67 have been opened by contact of the rear end of the arm 67 with the screw 71 and the feed slide moves forward, this spring will swing the arms together to cause the guides 66, 68 to engage the sole as shown; and this movement of the guide arm 67, in connection with mechanism presently to be described, causes the opening and closing not only of the two sets of guides 66, 68 and 77, 79, but of two similar sets of guides which are mounted upon the feed slide 17. The two sets of guide mechanism mounted upon the feed slide 17 are substantially like those mounted upon the feed slide 16. The breast-line set comprises two arms 87, 89 having upstanding lugs or guides 91, 93 at their forward ends; the arms being pivoted to the slide and geared together in the same manner as are the arms 65, 67. The ball-line set comprises two guides 95, 97 which are mounted upon the slide 17 in the same manner as that in which the guides 77, 79 are mounted upon the slide 15.

A rod 99 connects all four of the two sets of guides in the following manner. The rod is sustained by two sleeves 101, 103 pivotally carried respectively at the outer ends of arms 115, 117 which are integral respectively with the links 75 and 119. The arm 83 is pivotally connected with a sleeve 121; and an arm 123, which corresponds to the arm 83, is pivoted to a similar sleeve 125. Threaded upon the rod 99 and adjustably held in place by set screws are three collars 127, 129 and 131. It has been explained that the arm 83 is connected to the feed slide 15 by a tension spring 85. In a similar manner the arm 115 is also connected to the feed slide 15 by a tension spring 133, and the arms 123 and 117 are connected respectively

to the feed slide 17 by tension springs 135, 137. When, therefore, the feed slides are retracted to their rearmost positions, and the extreme rear end of the arm 67 strikes the end of the screw 71, the arm 83, by engagement with the head 139 on the left-hand end of the rod 99, pulls the rod to the left. The fixed collar 129 at the same time pushes the sleeve 125 to the left thereby opening the guides 91, 93; and during the movement of the rod to the left the collars 127, 131 engage respectively the sleeves 101 and 103 and push them to the left, thereby opening the ball-line guides 77, 79 and 95, 97. As soon as the feed slides move forward far enough so that the screw 71 no longer contacts with the extreme end of the arm 67, the tension springs close the guides upon the soles as shown in Fig. 1.

20 Power is applied to the shaft 45 in any approved manner. A chain 141 passes around a sprocket 143 fast to one end of the shaft 45 and around a smaller sprocket 145 fast to the shaft 61 on which the matrix roll 105 is mounted. A second chain 147 passes around a sprocket 149 on the shaft 61 and around a sprocket 151 fast to the shaft 59 of the other matrix roll. The presser rolls 7 and 107 are driven respectively from gears, one of which is shown at 152, fast, respectively, to the shafts 59 and 61. The small feed rolls 51, 53 are geared together, and the roll 51 is driven through an idle gear 157 which meshes with the gear 153 and with a gear, not shown, on the shaft of the feed roll 51.

25 The soles, which are to be operated upon, are first sorted into groups according to their lengths. The rod 19 is then turned to adjust the feed mechanism so that it will deliver properly the soles of a given group. The soles of this group are then placed one by one upon the feed slide 15 when said slide is in its rearmost position and the two sets of guides 66, 68 and 77, 79 are open, and are fed through the machine in the manner which has been described. After the soles of one group have been operated upon the machine is brought to rest and the rod 50 19 turned to adjust the feed mechanism for a second group.

30 Although the invention has been set forth as embodied in a particular machine, it should be understood that the invention is not limited in the scope of its application to the particular machine which has been shown and described.

Having thus described my invention, what I claim as new and desire to secure by Letters Patent of the United States is:—

35 1. A machine of the class described having, in combination, means for making two overlapping scarfs each of a fixed and predetermined length on the margin of a blank to produce a composite scarf, and means for

varying the extent of the overlap to vary the extent of said composite scarf.

2. A machine of the class described having, in combination, means for making on the margin of a blank two separate scarfs which overlap at their adjacent ends so as to produce a composite scarf of a length greater than that of either of the separate scarfs, and means for varying the locations of the separate scarfs in such manner as to change the extent of their overlap and thereby the length of the composite scarf produced.

3. A machine of the class described having, in combination, two mechanisms adapted each to make a cut in a blank, and means for causing the blank to be operated upon by said mechanisms in succession in such manner that the cuts overlap to produce a composite cut longer than either of the separate cuts.

4. A machine of the class described having, in combination, two mechanisms adapted each to make a cut in a blank, means for causing the blank to be operated upon by said mechanisms in succession in such manner that the cuts overlap to produce a composite cut longer than either of the separate cuts, and means for varying the location of the separate cuts to vary the extent of their overlap.

5. A machine of the class described having, in combination, two mechanisms arranged in series and adapted each to make a cut in a blank fed to them, and means for feeding a blank in such manner that the cuts overlap to produce a composite cut longer than either of the separate cuts.

6. A machine of the class described having, in combination, two mechanisms arranged in series and adapted each to make a cut in a blank fed to them, means for feeding a blank in such manner that the cuts overlap to produce a composite cut longer than either of the separate cuts, and means for varying the operation of the feeding means to change the extent of the overlap of the separate ends and thereby the length of the composite cut.

7. A machine of the class described having, in combination, two cutting mechanisms arranged in series, each adapted to make a cut of fixed extent in a blank fed to it, and means for feeding a blank to said mechanisms in succession in such manner that a selected axis of the blank bears the same relation to both mechanisms and the cuts are caused to overlap whereby one cut forms an extension of the other to produce a composite cut which is longer than either of the successive cuts.

8. A machine of the class described having, in combination, two cutting mechanisms arranged in series, each adapted to make a cut of fixed extent in a blank fed to it, means for feeding a blank to said mechanisms in

- succession in such manner that a selected axis of the blank bears the same relation to both mechanisms and the cuts are caused to overlap whereby one cut forms an extension of the other to produce a composite cut which is longer than either of the successive cuts, and means for adjusting the feeding means to vary the extent of the overlap. 5 70
10. 9. A machine of the class described having, in combination, two mechanisms arranged in series and adapted to make connecting cuts in a blank, two feed mechanisms one associated with each cutting mechanism and having movable blank-engaging members, and means for varying the locations of the paths of movement of said movable members to vary the locations of the cuts in the blank. 15 75
20. 10. A machine of the class described having, in combination, two mechanisms arranged in series and adapted to make connecting cuts in a blank, two feed mechanisms one associated with each cutting mechanism and having movable blank-engaging members, and means for varying to different extents the locations of the paths of movement of said movable members to vary the locations of the cuts in the blank. 25 80
30. 11. A machine of the class described having, in combination, two mechanisms arranged in series and adapted to make connecting cuts in a blank, two feed mechanisms one associated with each cutting mechanism and having movable blank-engaging members, and means for simultaneously and differently varying the locations of the paths of movement of said movable members to vary the locations of the cuts in the blank. 35 85
35. 12. A machine of the class described having, in combination, a plurality of skiving mechanisms, feed slides associated one with each mechanism, and means reciprocating the feed slides in unison toward and from their respective skiving mechanisms, the path of reciprocation of one slide being spaced a greater distance from its skiving mechanism than is the path of the other feed slide. 40 90
45. 13. A machine of the class described having, in combination, a plurality of skiving mechanisms, feed slides associated one with each mechanism, means reciprocating the feed slides in unison toward and from their respective skiving mechanisms, the path of reciprocation of one slide being spaced a greater distance from its skiving mechanism than is the path of the other feed slide, and means for changing the locations of said paths. 50 95
55. 14. A machine of the class described having, in combination, two skiving mechanisms arranged in series, feed mechanisms one associated with each skiving mechanism, connections between said feed mechanisms such that they are operated in unison, and means for adjusting the feed mechanisms into different initial positions to vary the localities on the work at which the skiving mechanisms operate. 60 100
65. 15. A machine of the class described having, in combination, two skiving mechanisms arranged in series, feed mechanisms one associated with each skiving mechanism, connections between said feed mechanisms such that they are operated in unison, and means for simultaneously adjusting the feed mechanisms into different initial positions to vary the localities on the work at which the skiving mechanisms operate. 70 105
75. 16. A machine of the class described having, in combination, a plurality of skiving mechanisms each comprising a matrix roll, feed members for each mechanism, means for moving the feed members in paths the extent of which is fixed, and means for varying the location of said paths to vary the localities on the work at which the skiving mechanisms operate. 80 110
80. 17. A machine of the class described having, in combination, two skiving mechanisms arranged in series and each comprising a matrix roll, feed mechanisms associated one with each skiving mechanism and each comprising a feed slide for engaging the work, a connection between the feed slides, and means whereby the effective length of the connection may be varied. 85 115
85. 18. A machine of the class described having, in combination, two skiving mechanisms arranged in series and each comprising a matrix roll, two feed slides associated respectively with the two skiving mechanisms, means for operating the feed slides, means for adjusting the feed slides to different extents, and means for delivering blanks from the first skiving mechanism to the second feed slide. 90 120
90. 19. A machine for skiving the shank of a sole having, in combination, a plurality of skiving mechanisms, one mechanism being adapted to produce the forepart of the desired scarf and the other to produce the rear part, and means for feeding the sole to said mechanisms in succession. 95 125
95. 20. A machine for skiving the shank of a sole having, in combination, a plurality of skiving mechanisms, one mechanism being adapted to produce the forepart of the desired scarf and the other to produce the rear part, means for feeding the sole to said mechanisms in succession, and means for varying the operation of the feeding means to vary the localities on the blank at which the skiving mechanisms operate. 100 130
100. 21. A machine for skiving the shank of a sole having, in combination, a plurality of skiving mechanisms each comprising a matrix roll, feed slides associated one with each mechanism, means for reciprocating the

slides in unison, and an adjusting member connecting the feed slides, manipulation of which changes the locations of the paths of reciprocation in the same direction but to a different extent.

22. A machine for skiving the shank of a sole having, in combination, two skiving mechanisms arranged in series each comprising a matrix roll, feed slides one associated with each mechanism, means for reciprocating the feed slides in unison, means for delivering the sole from the first skiving mechanism to the second feed slide, and two guiding means associated one with each feed slide for engaging opposite edges of the sole.

23. A machine for skiving the shank of a sole having, in combination, two skiving mechanisms arranged in series each comprising a matrix roll, feed slides one associated with each mechanism, means for reciprocating the feed slides in unison, means for delivering the sole from the first skiving mechanism to the second feed slide, and two guiding means associated one with each feed slide for engaging opposite edges of the sole, the two guiding means being movable with their respective feed slides.

24. A machine of the class described having, in combination, means for making two scarfs each of a fixed and predetermined length on the margin of a blank to produce a composite scarf, and means for varying the points on the blank at which the scarfs begin.

25. A machine of the class described hav-

ing, in combination, two cutting mechanisms for making two scarfs on the margin of a blank to produce a composite scarf, and means for feeding the blank successively to the mechanisms.

26. A machine for skiving the shank of a sole having, in combination, two skiving mechanisms arranged in series each comprising a matrix roll, feed slides one associated with each mechanism, means for reciprocating the feed slides in unison, means for delivering the sole from the first skiving mechanism to the second feed slide, two guiding means associated one with each feed slide for engaging opposite edges of the sole, the guiding means comprising guide members adapted to engage opposite edges of the sole, and means for opening said members to permit the sole to be placed between them and for thereafter closing the members upon the sole.

27. A machine for skiving the shank of a sole having, in combination, a skiving mechanism, a feed slide for presenting the sole to the skiving mechanism, separable guide members mounted upon the slide and adapted to engage opposite edges of the sole, and means for separating the members when the feed slide is retracted and for causing the members to close upon the sole when the slide moves forward.

In testimony whereof I have signed my name to this specification.

WILLIAM C. STEWART.
